PIVOTED FORMING DIE FOR RECIPROCATING METAL PLATE BENDERS

William T. Glud, Bremerton, Wash.

Application April 20, 1945, Serial No. 589,446

2 Claims. (Cl. 153—33)

(Granted under the act of March 3, 1883, as amended April 30, 1928; 370 O. G. 757)

1

This invention relates to a forming die and more particularly to a forming die of the dual action type.

In the formation of articles by means of press and die, the die is customarily of single piece, rigid construction. Such a conventional die is found satisfactory in the formation of articles with relatively shallow indentations. However, in production procedures involving the pressing of sheets of metal, plastic or other material to conform to deep or extensive configurations of a die, formation stresses, strains and frictional effects on the material cause imperfections resulting in rejection by inspectors of many articles produced.

It is an object of my invention to provide an improved forming die having the advantage of converting part of the vertical motion of a press into rotational movement of portions of the die, expeditiously to form objects by reducing the formation stresses and strains and undesirable frictional effects on the material being shaped.

Other objects of the present invention are to provide an improved forming die capable of speedily forming articles of accurately positioned configuration; to promote the safety of an operator of a press associated with the forming die making the handling of the material within the press unnecessary; to provide an improved forming die from which formed articles may be speedily and easily removed, and to provide improved elements and arrangements thereof in a forming die of the character and for the purposes set forth.

In accomplishing these and other objects of the present invention, I have provided improved details of structure, the preferred form of which is illustrated in the accompanying drawing, wherein:

Fig. 1 is a perspective view of a dual action forming die embodying the features of the present invention and showing a conventional ram member supported thereabove in operating position.

Fig. 2 is a detail cross sectional view of a dual action forming die, the article formed in the die, and the conventional ram being shown in their respective positions at the end of the downward stroke of said ram member.

Referring more in detail to the drawing:

The dual action forming die is supported by a box-like base member, substantially rectangular in shape, consisting of a foundation plate 1, of a material strong enough to support the die during pressing operations. A pair of end plates 2 and

2

a pair of side plates 3 are weldably secured substantially perpendicular to the foundation plate to form a frame and retaining walls for the die forming bed or box-like base member.

Extending and arranged longitudinally within the box are a pair of rectangular bearing blocks 4, each having a concave, semi-cylindrical bearing surface 5 extending throughout their length.

A plurality of shims 6 arranged on the outer 10 side faces of the blocks and within the bed and end plates constrain the bearing blocks 4 in parallel relationship within the box-like base member. By varying the placing of said shims 6, the bearing blocks 4 may be spaced as desired in respect to each other and in respect to the side 15 plates 3 for each design to be pressed. For example, shims may be also arranged between the blocks 4 to properly space the same. In this connection it will be apparent that a sufficient number of shims 6 are used to wedge the bearing blocks 4 securely into place in the bed.

A pair of elongated angular rocker arms 7 and 8, having lower convex, semi-cylindrical bearing surfaces 9 and 10, are pivotally mounted on the 20 concave bearing surfaces 5 of the bearing blocks 4. The rocker arms 7 and 8 have outwardly directed laterally extending arm portions 11 and 12 with substantially flat top surfaces 13 and 14 for receiving and supporting a blank of sheet material 30 to be formed. The inwardly facing surfaces 15 and 16 of the rocker arms 7 and 8 are grooved as shown to receive and support bite adjustment plates 17 and 18 presently more fully described. Said surfaces 15 and 16 have longitudinal lips 19 35 and 20 projecting inwardly to support and act cooperatively with a depth control plate also presently described.

Width control plates 21 and 22 are adjustably mounted on surfaces 13 and 14 by wing bolts 40/23 passed through elongated openings 24 in the arms of the width control plates, the bolts being threadedly engaged with the rocker arms 7 and 8.

Adjustable gauge blocks 25 and 26 are supported by the width control plates 21 and 22. Said adjustable gauge blocks 25 and 26 are clamped in position by set screws 27 and 28, thus permitting a blank of material to be inserted only as far as desired.

The bite adjustment plates 17 and 18 are the 50 working surfaces for the rocker arms 7 and 8. By loosening adjustment bolts 29 and 30 that are threadedly engaged through elongated openings in bite adjustment plate mounting arms 31 and 32, said bite adjustment plates 17 and 18 may be 55 adjusted in relation to their respective rocker

arms 7 and 8 as desired. The elongated openings, concealed from view in Fig. 1 by the bolts 29 and 30 and their washers, extend in the direction of the long sides of the rectangular arms 31 and 32 and thus constitute conventional slots permitting sliding adjustment of the arms 31 and 32 relative to the bolts 29 and 30, respectively. This sliding adjustment enables the plates 17 and 18 to be brought snugly against the rocker arms 7 and 8, respectively since the arms 31 and 32 are made integral, as by welding, with the plates 17 and 18, respectively. The removal of said adjustment bolts 29 and 30 at each end of rocker arms 7 and 8 permits the removal of the bite adjustment plates 17 and 18 and the substitution therefor of bite adjustment plates of various configurations.

33 designates a depth control plate supported by the lips 19 and 20 on the rocker arms. The control plate 33 is slidably guided in a vertical direction by pegs 34 and 35 passed through holes in the depth control plate and rigidly secured to the foundation plate 1 in vertical position. The depth control plate 33 may be made in various forms desired to be impressed in the material. By different choices of forms of depth control plate 33 and, of course, the corresponding cooperating male die member hereinafter described, material may be fashioned in various shapes either for structural or ornamental purposes. For example, while the material shape illustrated is generally in the form of a U with a concave lower portion, it is possible to form the lower portion either flat or convex with different degrees of curvature.

Adjustment gauges 36 are supported in adjustable relationship to the side plates 3 by adjustment bolts 37 threadedly engaged to the adjustment gauges 36 through substantially vertically arranged elongated openings in the side plates 3. The adjustment gauges 36 support the outwardly directed arm portions 11 and 12 of rocker arms 7 and 8 in relaxed position. The vertical adjustment of gauges 36 provides an additional method of regulating the relative positioning of the bite adjustment plates 17 and 18.

38 designates handles that are rigidly secured to the outwardly directed arm portions 11 and 12 of the rocker arms 7 and 8 and permit the manual operation of the dual action forming die.

39, Fig. 2, designates a piece or blank of sheet material acted upon and formed by the mutual action of a ram member 40 and a male die member 41. The ram and male die members are not parts of the invention, but are shown to coact with and motivate the dual action forming die. These members are affixed to a press in a suitable manner and the press is actuated conventionally.

42 designates a centering gauge mounted on the end plate 2 and is useful in positioning the rocker arms 7 and 8, the material being formed, and the dual action forming die in relation to the ram member.

Operation

The operation of a forming die constructed as described is as follows:

The shims 6 are so placed within the box-like base member as to wedge the bearing blocks 4 in the desired position for the operation to be performed.

The angular rocker arms 7 and 8 are placed on the bearing blocks 4 in such a manner that their convex bearing surfaces 9 and 10 may turn freely within the concave bearing surfaces 5.

The adjustment gauges 36 are secured at the

desired height by tightening the adjustment bolts 37. This height of adjustment controls the tilt of the rocker arms 11 and 12 and affects the amount and angle of opening of the bite adjustment plates 17 and 18.

The width control plates 21 and 22 are adjusted to receive the blank of sheet material to be formed and are secured in such adjustment by tightening the wing bolts 23.

The distance the blank of sheet material can be shoved into the die is regulated by securing the gauge blocks in position by tightening set screws 27 and 28.

15 Bite adjustment plates 17 and 18 are secured in desired adjusted position by tightening bolts 29 and 30 on both ends of the die.

20 The depth control plate 33 is placed slidably upon pegs 34 and 35 so as to overlap the lips 19 and 20. The depth control plate 33 and the bottom male die portion 41 of the ramming member 40 being of complementary configuration, the desired shaping or forming of the metal blank may be thus effected.

25 Guided by the width control plates 21 and 22 and the adjustable gauge blocks 25 and 26, the blank of material to be formed is positioned on the dual action forming die.

30 As the ramming member 40 descends, the male die 41 comes in contact with the blank of sheet material supported on surfaces 13 and 14. The continued downward motion of said die 41 causes the blank of sheet material to be bent downwardly in the middle. The bending action shortens the blank of sheet material and tends to rotate the rocker arms 7 and 8 inwardly through the friction of the material being formed on surfaces 13 and 14 and bite adjustment plates 17 and 18. Said frictionally transmitted force continues to rotate the rocker arms 7 and 8 inwardly as the male die 41 descends.

35 Near the bottom of the stroke the male die 41 presses the material being formed against the depth control plate 33 with force sufficient to cause the material being formed to conform to 40 the configurations of the male die 41 and depth control plate 33.

45 The depth control plate 33 transmits the downward force of the press to the lips 19 and 20 of the rocker arms 7 and 8 which in turn positively 50 rotate the rocker arms 7 and 8 inwardly pressing the bite adjustment plates 17 and 18 inwardly against the material being formed. Said inward movement of the bite adjustment plates 17 and 18 is controlled by regulating the extent of the 55 downward movement of the press. It may be augmented by force applied to the handles 38.

50 As the ramming member 40 and male die 41 move upward, the depth control plate 33 is relieved of the depressing force. The weight of the outwardly directed arm portions 11 and 12 of the rocker arms 7 and 8 overbalance the rocker arms 7 and 8 and rotate the said rocker arms outwardly, open the bite adjustment plates 17 and 18, transmit an upward motion to the depth control plate 33 through the lips 19 and 20 and eject the formed article 39 from the dual action forming die. The amount that the formed article 39 is lifted from the dual action forming die by the depth control plate 33 is dependent 65 upon the amount of outward rotation of the rocker arms 7 and 8 permitted by the throw adjustment gauges 36.

70 This ejection of the formed article 39 facilitates 75 its speedy removal and makes way for a quick

insertion of another blank of sheet material and a repetition of the process.

It is by virtue of the combined forming action exerted on the workpiece by the male die member 41 and the female element of the die, comprising the rocker arms 7 and 8 and their associated structure, as described above, that the apparatus forming the subject of the present invention is referred to herein as a "dual action forming die."

It is apparent, therefore, that I have provided a dual action forming die having the advantages of converting part of the vertical motion of the press into rotational movement of portions of the die whereby stresses, strains, and undesirable frictional effects of formation are vastly reduced; wherein articles of accurately positioned configuration may be formed; where the handling of the material during formation is unnecessary; and wherefrom formed articles may be speedily and easily removed.

The terms "sheet" and "sheet material" are employed herein in their generic sense, and they are intended primarily to embrace heavy gauge material of the type commonly known as "plate." They also embrace various shapes of material, whether straight or partially preformed, such as bars, rods, and the like.

While I have shown but one embodiment of my invention, it is apparent that the device is susceptible to modification without departing from the spirit of the invention. I do not wish, therefore, to be limited by the disclosures set forth, but only by the scope of the claims.

The invention described herein may be manufactured and used by or for the Government of the United States of America for governmental purposes without the payment of any royalties thereon or therefor.

I claim:

1. A dual action forming die comprising a box-like foundation member substantially rectangular in shape; a pair of rectangular bearing blocks longitudinally positioned within the base member, each block having a semi-cylindrical concave bearing surface extending throughout its length; a plurality of shims contained within said base member to constrain in adjustable parallel relationship the said bearing blocks; a pair of elongated angular rocker arms having lower bearing surfaces pivotally supported in said bearing blocks and outwardly directed arm portions having substantially flat surfaces provided to receive sheet material to be formed and inwardly facing surfaces each having longitudinal, inwardly projecting lips thereon; a pair of bit adjustment plates mounted on the inwardly facing surfaces of said rocker arms adapted formatively to engage the sheet material from the frictional moment of said material to impart an inward rotational

motion to the rocker arms; a pair of adjustable width control plates supported on the rocker arms provided to position the said sheet material on the die; a pair of gauge blocks mounted on

5 the said width control plates constituting stops for the inserted material; a depth control plate having guide openings formed therein positioned between the rocker arms and supported by the inwardly projecting lips thereof; guide pegs passed through the openings in the depth control plate and rigidly secured to the foundation member for slidably guiding the control plate in vertical direction; a centering gauge mounted and centered on a portion of the foundation member; 10 and a pair of throw adjustment gauges supported by the sides of the foundation member in a position to support the outer portions of the rocker arms in a relaxed position, said throw adjustment gauges being adapted to control the initial opening between the bit adjustment plates.

2. A female die assembly comprising a support; a pair of parallel bearing blocks arranged for adjustment in any predetermined spaced relationship on said support; an elongated rocker 15 arm pivotally mounted adjacent one end thereof in each of said bearing blocks and having its other end disposed outwardly of said blocks; an inwardly disposed lip means carried by each rocker arm above its surface of pivotal engagement with its bearing block; a depth control plate supported between said lip means; and gauge means mounted on said support adjacent the outwardly disposed end of each of said arms for controlling the degree of outward pivotal movement of said arms; the adjacent, upper surfaces of said arms being disposed formatively to engage adjacent surfaces of a workpiece placed over the female die as the workpiece is initially pressed inwardly thereof, and said arms being arranged 20 to rotate inwardly on said bearing blocks by the frictional engagement of the workpiece with the said arm surfaces.
